United States Patent Office.

JOHN HENDERSON, OF ALBION, NEW YORK.

Design No. 4,015, dated May 10, 1870.

DESIGN FOR BREAST-STRAP SLIDE.

The Schedule referred to in these Letters Patent and making part of the same.

I, JOHN HENDERSON, of Albion, in the county of Orleans and State of New York, have invented and produced a new and original Design for Breast-strap Slides for Harnesses, of which the following is a specification.

The nature of my design is fully represented in the accompanying drawings, to which reference is made.

Figure 1 is a perspective view, showing the sides A A, connected by the pieces B B B and C C, so that the strap may pass over B B B, and under C C. At D the sides A A and center cross-piece B are hol-

lowed out to receive the neck-yoke ring, which would, otherwise, wear the strap.

Figure 2 is an under-side view of fig. 1.

Claim.

I claim as my invention—

The design for a breast-strap slide, as shown.

JOHN HENDERSON.
